DESIGN FOR A PUMP

John G. Baker, Jackson Heights, N. Y.

Application October 15, 1942, Serial No. 108,533

Term of patent 7 years

To all whom it may concern:

Be it known that I, John G. Baker, a citizen of the United States, residing at Jackson Heights, in the county of Queens and State of New York, have invented a new, original, and ornamental Design for a Pump, of which the following is a specification, reference being had to the accompanying drawing, forming part thereof, and in which:

Figure 1 is a side elevational view of a pump, showing my new design; and

Figure 2 is a front elevational view of the same.

I claim:

The ornamental design for a pump, as shown.

JOHN G. BAKER.
